UNITED STATES PATENT OFFICE.

JACOB H. HODDE, OF SPRINGFIELD, ILLINOIS, ASSIGNOR TO SANGAMO ELECTRIC COMPANY, OF SPRINGFIELD, ILLINOIS, A CORPORATION OF ILLINOIS.

ELECTRIC MERCURY-MOTOR METER.

No. 878,629.

Specification of Letters Patent.

Patented Feb. 11, 1908.

Application filed March 16, 1907. Serial No. 362,775.

To all whom it may concern:

Be it known that I, JACOB H. HODDE, a citizen of the United States, residing at Springfield, county of Sangamon, State of Illinois, have invented certain new and useful Improvements in Electric Mercury-Motor Meters, of which the following is a specification, reference being had to the accompanying drawings.

10 My invention relates to improvements in electric mercury motor meters. In this type of meter, as is well known, the armature, usually a copper disk, is mounted on a vertical spindle and immersed in mercury.

15 This disk is usually amalgamated, completely or in part, before being placed in the meter, but even when this is not done the copper disk soon becomes more or less completely amalgamated in ordinary use. When

20 such a meter having the more or less completely amalgamated armature immersed in mercury is shaken about, as it must be necessarily in shipment, the amalgam oxidizes and rises to the surface of the mercury.

25 This oxidized amalgam or dross, gathering about the spindle and filling up the depression about the spindle caused by capillarity, as will be readily understood, and forming a cohesive film on the upper surface of the

30 mercury, adheres to the spindle and to the body of the mercury, having a considerable retarding effect upon the armature on light load current, and causing the meter on such load to register considerably less than the

35 amount of power actually used.

The object of this invention is to provide means by which this retarding effect may be overcome or made so small as to be unappreciable. I accomplish this object by the

40 means illustrated in the drawings and hereinafter described.

What I consider as new is pointed out in the claims.

In the drawings.—Figure 1 is a side elevation of the meter. Fig. 2 is a view similar to Fig. 1, but showing a central cross-section of the casing in which the mercury chamber is formed, and showing the parts inside the casing in elevation. Fig. 3 is an illustration of another form of the device for preventing the retarding effect of the dross. Fig. 4 is a detail, being a section very much enlarged through one end of the washer for the purpose of showing the amalgamation on the lower surface.

Referring to the several figures of the drawings, in which corresponding parts are indicated by like reference characters, 10, 11 indicate the two parts of the body of the casing in which is formed the mercury chamber 12 containing mercury 13. Submerged in the mercury are the armature 14 and flotation chamber 15, both non-rotatably secured on spindle 16 which is suitably journaled in the ordinary manner. Near the upper end of the spindle is shown a braking disk 17 acted upon by permanent magnets 18, as usual.

19 indicates the contacts entering the mercury chamber and adapted to carry the driving current.

20 indicates an electro-magnet energized by coil 21 which is to be connected up as desired. As illustrated, the poles of the magnet 20 pierce the part 11 of the casing, the ends of the said poles being thus brought in close proximity to the armature 14.

22 indicates a plate, preferably of soft steel, adapted to serve as a return for the magnetic lines of force from pole to pole of the magnet 20.

Referring to Fig. 2, 23 indicates a washer,—preferably of non-amalgamable metal, though it may be of any other suitable material,—surrounding the spindle 16, in the construction shown, and floating on the surface of the mercury. It is not necessary that the washer shall float on the mercury, but only that it shall effectively protect the spindle at the point where the spindle enters the body of the mercury, as is hereinafter explained.

It is, of course, necessary that the opening in the washer shall be large enough that the washer cannot bind on the spindle. It has been found in practice that an opening having a diameter from ten to fifteen thousandths of an inch larger than the diameter of the spindle produces very satisfactory results, but I do not wish to restrict myself to the use of such a close-fitting washer, or other device. In order that the washer shown shall not bind on the spindle in case the meter should be tipped slightly from its normal upright position, I have reamed out the opening in the washer from both sides, thus presenting a minimum bearing surface to the spindle, and reducing this objection as much as possible. This, of course, is not ordinarily necessary to the proper working of the meter.

When the oxid has been formed in the mercury chamber in shipment, as above explained, and the meter is to be hung up for use, it is a very simple matter to shake and 5 turn the meter so as to get this oxid or dross on the surface of the mercury beyond the washer, where it is kept from contact with the spindle. The lower surface of the washer is preferably amalgamated. While 10 this causes such under surface to have a stronger attraction for the dross, at the same time it causes said under surface to have a still stronger attraction for the mercury, which condition aids materially in getting 15 this dross from under the washer.

As has been stated above, the body of the washer is preferably of non-amalgamable material. It has been found that this dross in the mercury does not adhere to a non- 20 amalgamable material nearly so strongly as it does to one that will amalgamate or is amalgamated. When a small amount of this dross does work its way into the bearing between the spindle and the washer, the 25 retarding effect is not nearly so great when such bearing is of non-amalgamable material as it would be if the bearing surface of the washer were amalgamable and had consequently a greater attraction for the dross. 30 It has been found that when the dross does get into the bearing as above suggested, it is very soon changed from a more or less cohesive body to the form of a fine dry powder, and in this form gradually works itself 35 out of the bearing so as not to retard the rotation of the spindle.

Fig. 3 shows another construction of the part that surrounds the spindle at the surface of the mercury. In this form the device for 40 preventing the accumulation of dross around the spindle 16 consists of a hollow cylindrical shaped float 24 provided at each end with a suitable opening through which the spindle 16 passes so that the said spindle rotates 45 freely therein.

So far as I am aware, no one has heretofore contemplated providing a spindle rotating in mercury with a device for protecting the spindle as described, and this feature is 50 therefore claimed broadly. While I have described this device as a "washer", this word, it will of course be understood, in both the specification and the claims is used for con-

venience in description, and is to be understood as referring to a device of the general 55 character described and not to be limited to the strict technical meaning of the word.

When the washer or drum is made of non-amalgamable metal, it will be readily understood that its under surface may be amalgamated in any well-known manner, such, for instance, as copper-plating its under surface and amalgamating the plated surface. This construction is shown in Fig. 4, which is a detail, showing a section of the washer very 65 much enlarged. In this figure 23 indicates the disk; 25 the copper plating; and 26 the amalgamation of the copper plated surface.

What I claim as my invention and desire to secure by Letters Patent is:—

1. The combination with a body of mercury and a spindle rotating therein, of a washer loosely surrounding said spindle at the point where the spindle enters the body 70 of the mercury.

2. The combination with a body of mercury and a spindle rotating therein, of a washer floating on the surface of the mercury and loosely surrounding the spindle.

3. The combination with a body of mercury and a spindle rotating therein, of a washer loosely surrounding said spindle at the point where it enters the body of the mercury, said washer being amalgamated on 80 its lower surface.

4. The combination with a body of mercury and a spindle rotating therein, of a washer of non-amalgamable material loosely surrounding said spindle at the point where it enters the body of the mercury.

5. The combination with a body of mercury and a spindle rotating therein, of a washer of non-amalgamable material loosely surrounding said spindle at the point where it enters the body of the mercury, said washer being provided with an amalgamated 95 under surface.

6. The combination with a body of mercury and a spindle rotating therein, of a hollow drum loosely surrounding the spindle 100 at the point where it enters the body of the mercury.

JACOB H. HODDE
